FURNITURE BASE

Ronald Beckman, New York, N.Y., and Rodney Y. Hatanaka, Montreal, Quebec, Canada, assignors to Herman Miller, Inc., Zeeland, Mich., a corporation of Michigan

Filed Jan. 25, 1963, Ser. No. 73,310

Term of patent 14 years

(Cl. D33—14)

FIG. 1.

FIG. 2.

FIG. 3.

FIG. 4.

FIG. 6.

FIG. 5.

FIG. 1 is a perspective view of the furniture base of this invention;

FIG. 2 is a side elevation of the base as viewed from the front as shown in FIG. 1;

FIG. 3 is a side elevation of the base as viewed from the right as shown in FIG. 1;

FIG. 4 is a reduced plan view of the base as shown in FIG. 1;

FIG. 5 is a reduced bottom view of the base as shown in FIG. 1; and

FIG. 6 is a cross-sectional view taken along the plane VI-VI of FIG. 1.

The side not shown in FIG. 1 is like the side shown in FIG. 2.

We claim:

The ornamental design for a furniture base, substantially as shown and described.
